UNITED STATES PATENT OFFICE.

GEORGE S. TOMPKINS AND CHARLES WHITTINGHAM, OF DETROIT,
MICHIGAN; SAID WHITTINGHAM ASSIGNOR TO SAID TOMPKINS.

COMBINED BRACKET AND CLAMP FOR PILLOW-SHAM HOLDERS.

SPECIFICATION forming part of Letters Patent No. 407,307, dated July 16, 1889.

Application filed October 15, 1888. Serial No. 288,166. (No model.)

To all whom it may concern:

Be it known that we, GEORGE S. TOMPKINS and CHARLES WHITTINGHAM, citizens of the United States, residing at Detroit, in the county of Wayne and State of Michigan, have invented certain new and useful Improvements in a Combined Bracket and Clamp for Pillow-Sham Holders; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to "pillow-sham holders," and particularly to a combined bracket and clamp, whereby the parts are made self-attaching to the bedstead, all of which will be hereinafter fully set forth. By this arrangement of bracket and clamp the pillow-sham holder can be rapidly attached to the bedstead, and at any desired position, without the aid of screws or brads of any kind, which require driving into the wood-work, thereby defacing the furniture.

With reference to the accompanying drawings, forming a part of the specification, we will proceed to describe the various parts of our device, the essential features being pointed out particularly in the claims.

As illustrated by the drawings, Figure 1 represents a perspective view of our invention in position and supporting a pillow-sham holder. Fig. 2 is a side plan of the bracket and clamp. Fig. 3 is a top plan showing the parts clamped to the rail of the head-board of a bedstead, the dotted lines showing adjusted position of clamp and bracket. Fig. 4 is a perspective view of the various parts detached constituting the combined bracket and clamp.

In the drawings, H represents the head-board of the bedstead, and R the end rails. Z and Z' represent the common sliding rails of a pillow-sham-holder frame, which support the wire-frame J.

The heads H' are supported in the forked ends n of the L-shaped brackets A, as shown in Fig. 1.

D represents the base of the clamp. This

base-plate has the oblong opening S and right-angle jaw C, through which the screw-threaded bolt B passes and revolves in the hole a and a like hole (not shown) through the opposite end of the base. The reduced end of the bolt is upset at i, (see Fig. 4,) whereby the said bolt is supported at both ends within the base-plate D. This bolt is provided with the thumb button or nut f, whereby the bolt B is revolved, for the purpose hereinafter set forth.

In Fig. 4, A illustrates the bracket, which is L-shaped and has a forked upper end, as shown at n.

F is a horizontal base, which is formed integral with the brackets, and t is a lug which projects from the front face of the base F and fits loosely in the open slot S of the base-plate D. The bracket A is reduced at O, where it joins the base F. Said reduced portion fits loosely into the opening S, as shown in Fig. 1.

W is a jaw formed integral with the base F and at right angles thereto, said jaw projecting from the rear end of said base.

In the base F is formed two screw-threaded holes a' a''. Through these holes the bolt B passes. By this construction it will be observed that as the bolt B is turned or rotated by means of the thumb-nut f the base F will be caused to travel or move horizontally along said bolt, the neck O and lug t sliding in the opening S, whereby the jaw W is caused to move toward or from the jaw C. The shifted position of the jaw W and bracket A is shown by dotted lines in Fig. 3.

E is a coiled-wire spring, which has two prongs c and c'. The prong c' enters the hole v in the bracket A, its end being bent, as shown at 3 in Fig. 2, whereby the spring is retained in position. The prong c of the spring presses against the head H' of the pillow-sham frame, whereby the frame is held in the fork n of the bracket A. The bracket A is secured to the bedstead in the following manner: The jaw C is placed against the outer face of the rail R of the bedstead. The screw-bolt B is then revolved by means of the thumb-button f, so as to cause the jaw W to advance and clamp the opposite face of said rail, thus firmly attaching the bracket which supports the pillow-sham frame.

As the jaw W is provided with means for

moving it toward and from the fixed jaw C, the bracket can be readily attached to the variously-shaped rails of bedsteads, and at any desired elevation, and the parts can be 5 detached from the bedstead at once.

Having thus set forth our invention, what we claim as new, and desire to secure by Letters Patent, is—

1. In combination with the L-shaped 10 bracket having the base and jaw formed integral therewith, and screw-threaded holes in the base thereof, the base-plate D, having the central opening with fixed jaw at one end thereof and holes in each end of the base, the 15 screw-threaded bolt engaging with the base F, having its ends journaled in the holes of the base-plate D, as and for the purposes specified.

2. In combination with the bracket A, having the forked upper end with base and jaw 20 W formed integral therewith, the base-plate D, having the oblong opening and holes in each end and jaw C at one end, the screw-threaded bolt having threaded engagement with the base of the bracket, its ends being 25 journaled in the base-plate D and carrying a button on one end, substantially as set forth.

In testimony whereof we affix our signatures in presence of two witnesses.

GEORGE S. TOMPKINS.
CHARLES WHITTINGHAM.
